UNITED STATES PATENT OFFICE.

EDWARD R. STETTINIUS, OF CHICAGO, ILLINOIS, ASSIGNOR TO THE
STIRLING COMPANY, OF SAME PLACE.

WATER-TUBE BOILER.

SPECIFICATION forming part of Letters Patent No. 628,044, dated July 4, 1899.

Application filed January 11, 1899. Serial No. 701,794. (No model.)

To all whom it may concern:

Be it known that I, EDWARD R. STETTINIUS, a citizen of the United States, residing at Chicago, in the county of Cook and State of Illinois, have invented a new and useful Improvement 5 in Water-Tube Boilers, of which the following is a specification.

The object of my invention is to improve water-tube boilers of the vertical type; and 10 the invention consists in the features and combinations hereinafter described and claimed.

In constructing a boiler in accordance with my invention I use an upper drum A, divided into compartments by diaphragms or partitions a and a', the former being perforated from bottom to top and the latter perforated above the water-line only, a lower drum B, having internal baffle-plates b and b', water-tubes C, communicating between the upper 15 and lower drums, fire-brick walls or partitions D and D', arranged vertically among the tubes, and a casing E, surrounding or inclosing the various parts forming the boiler proper.

There are of course a fireplace, a chimney, 20 and other parts or details; but as these will be readily understood no special description thereof is considered necessary.

In operation feed-water is introduced into the upper drum through the inlet a², behind the 25 vertical rear wall or partition D', and immediately passes down through the tubes into the rear portion of the lower drum, where, owing to previous heating, a considerable portion of its sediment is deposited, which sediment may be removed by a blow-off b² or otherwise. Passing 30 over the baffle-plate b and down under the baffle-plate b' the water goes forward in the mud-drum and up through the tubes forward of the front vertical wall or partition D into the front portion of the upper drum, whence, the perforated partition a not preventing, it again passes down through the tubes between the two vertical walls into the lower mud-drum, and so on in circuit.

The advantages of my invention are that it 45 provides, first, a compact construction having an upper drum and a lower drum, the former being subdivided into three different chambers to provide for the free circulation 50 of water without the danger of foaming or

unequal and irregular water-levels and a portion of the latter acting as a settling-chamber; second, for gradually heating the feed-water, before it passes into the hottest parts of the boiler, by steam passing through the 55 perforated portion of the rear diaphragm as well as by the escaping gases coming in contact with the tubes forming the rear bank, thus performing the functions of an economizer or live-steam purifier, and, third, the separation of the tubes into different banks is such that the gases are compelled to make three 60 passes in their passage to the stack, thus utilizing the highest possible proportion of the heat units contained in the fuel. 65

Although I prefer to use my improvements together, it will of course be understood that this is not necessary, the same being capable of separate use, and generally it will be understood that I do not intend to limit myself 70 to minor features or details of construction, it being my intention to vary form or construction, omit parts, or use equivalents as circumstances may suggest or render expedient.

I claim—

1. In a vertical water-tube boiler, the combination of an upper drum provided with a front an intermediate and a rear compartment separated one from the other by diaphragms permitting free communication between the front and intermediate compartments and closing communication except at the top between the intermediate and rear compartments, a lower mud-drum, tubes connecting the upper and lower drums, and vertical walls or partitions in the tube-chamber, one wall extending upward and the other downward dividing the tubes into sections corresponding to the compartments of the upper drum, substantially as described. 75 80 85 90

2. In a vertical water-tube boiler, the combination of an upper steam-and-water drum having a front an intermediate and a rear compartment, a diaphragm or partition between the front and intermediate compartments permitting free communication between the two, a diaphragm or partition between the intermediate and rear compartments closing communication between the two except at the top, a lower drum, tubes 95 100

- connecting the upper and lower drums, a vertical wall or partition extending upwardly between the tubes, a vertical wall or partition extending downwardly between the tubes, the
- 5 two walls alining with the diaphragms or partitions of the upper drum dividing the tubes into sections corresponding to the compartments of the upper drum for each section of tubes to have communication with its
- 10 compartment, substantially as described.
3. In a vertical water-tube boiler, the combination of an upper steam-and-water drum, a lower mud-drum having baffle-plates arranged therein in substantially vertical planes, one in
- 15 rear of the other, tubes connecting the upper and lower drums, a vertical wall or partition extending upwardly among the tubes from the lower drum to a point more than half the distance between the two drums, and a vertical
- 20 wall or partition in the rear thereof extending downwardly among the tubes from the upper drum to a point more than half the distance between the two drums, whereby the
- 25 course of the gases is directed in and among the tubes, substantially as described.

4. In a vertical water-tube boiler, the combination of an upper steam-and-water drum having two diaphragms therein arranged in vertical planes, the front diaphragm being perforated from bottom to top and the rear 30 diaphragm perforated above the water-line only, a lower mud-drum having baffle-plates arranged therein in substantially vertical planes, one in rear of the other, tubes connecting the upper and lower drums, a vertical wall or partition extending upwardly among the tubes from the lower drum to a point more than half the distance between the two drums, and a vertical wall or partition in the rear thereof extending downwardly among 35 the tubes from the upper drum to a point more than half the distance between the two drums, whereby the course of the gases is directed in and among the tubes, substantially as described.

EDWARD R. STETTINIUS.
